UNITED STATES PATENT OFFICE

2,502,036

ELECTRIC SHAVER

Earle E. Dietrich, Portsmouth, Va.

Application December 9, 1946, Serial No. 714,999

2 Claims. (Cl. 30—45)

1

This invention relates to electric razors.

An object of this invention is to provide a razor embodying a razor blade and an electric operator for the blade wherein the blade forms the vibrating armature associated with the iron core of the device.

Another object of this invention is to provide an electric razor which can be used either dry or with lather, and which is designed for using conventional razor blades of either the single or double edge type.

A further object of this invention is to provide an electric razor which uses the magnetic pulsations derived from alternating current to vibrate the razor blades, the latter being placed in juxtaposition with respect to the magnetized core so that the blade will be subjected to rapid and minute vibration.

A further object of this invention is to provide an electric razor which eliminates the make and break means of motors now in use so that the operator can be sealingly encased in a waterproof casing in order that the head portion of the device may be cleaned in water without short circuiting the operator.

A further object of this invention is to provide an electric razor of simple construction which eliminates all moving parts so that the motor or operator will not get out of order and will last indefinitely.

With the above and other objects in view, my invention consists in the arrangement, combination and details of construction disclosed in the drawings and specification, and then more particularly pointed out in the appended claims.

In the drawing,

Figure 1 is a detail front elevation, partly broken away, of an electric razor constructed according to an embodiment of this invention.

Figure 2 is a detail side elevation of the device.

Figure 3 is a fragmentary sectional view taken on the line 3—3 of Figure 2.

Figure 4 is a diagrammatic view of the operator embodied in this invention.

Figure 5 is a view similar to Figure 4, but at right angles to the latter.

Figure 6 is a diagrammatic view of a modified form of this invention.

Referring to the drawing, the numeral 10 designates generally an electric operator which includes a winding or coil 11 having a U-shaped core 12. The core 12, at its upper end, is formed with confronting extensions 13 which are spaced apart at their inner ends so as to thereby form an air gap 14.

2

The coil 11 is adapted to be connected to a source of alternating current supply and the pulsations of the cyclic current are adapted to be utilized in the vibratory operation of a razor blade, as will be hereinafter described.

The operator 10 has the coil 11 thereof enclosed in a casing or handle 15 which is of suitable configuration and length, and the lead wires 16 from the coil 11 are extended downwardly through the handle 15 and connected to contact members 17 in the lower or rear end of the handle 15. A plug or connector 18, having a pair of conductors 19 connected thereto, is adapted to be engaged with the contacts 17 and connected to a source of alternating current supply.

The outer portion or extensions 13 of the core 12 have mounted thereon a blade holder generally designated as 20. The holder 20 includes an inner plate 21 formed at the opposite ends with ears 22 engaging on the outer sides of the parallel legs of the core 12, and the plate 21 is formed with a front flange 23 having spaced ribs 24. A centrally disposed depending ear or lug 25 is carried by the flanges 23 and is adapted to be secured to the extensions 13 of the core 12 by means of a rivet or fastening member 26.

Suitable insulating means may be interposed between the ends of the fastening member 26 so that the air gap 14 between the ends of the extensions 13 will be maintained. The holder 20 is preferably formed of non-magnetic material so that the holder will not serve as a bridge between the ends of the core extensions 13. The holder 20 is also formed with a downwardly and rearwardly extending ribbed plate 27 having ribs 28 adapted to extend over the top of a blade 29. The blade 29 is removably mounted in the slot 30 formed at the ends of the upper plate 21 and the ends of the plate 21, including the flanges 22.

The cutting edge 31 of the blade 29 is adapted to overlie the ribs 24 and overlie the extensions 13 so that when the core 12 is energized, the magnetism thereof will be communicated to the blade 29. In this manner the blade 29 will be subjected to the same cyclic vibration as occurs in the core 12, due to the alternating current passing through the electro-magnetic coil 11.

As will be noted from Figure 5, the outer edges 50 of the core extensions 13 are also formed with spaced air gaps 32 so that these core extensions will be placed under the desired vibratory operation when the coil 11 is energized.

As will be noted from Figure 1, the handle 15 is disposed at an obtuse angle to the core 12.

this angle being provided to facilitate the engagement of the blade 29 when the device is in use.

Referring now to Figure 6, there is disclosed a modified form of this invention which is designed for use with double edged blades. A motor or operator 10a is provided, which has a coil 11a and a U-shaped core 12a is adapted to be magnetized when the coil 11 is energized. The outer free ends of the core 12a are disposed in relatively close proximity to the opposite cutting edges of a double edged blade 33, which is supported by means of a holder 34.

In the use and operation of this razor, the conductor 19 is connected to a source of alternating current supply thereby energizing the electro-magnetic coil 11. When the coil 11 is energized, core 12 will be magnetized and under cyclic vibration, this vibration being communicated to the core extensions 13. When the core extensions 13 are magnetized and under the cyclic pulsations of the electric current, blade 29 will be rapidly vibrated. The keen edge 31 may be moved over the face, and if desired, the face may be coated with lather or the face may be dry. The rapid pulsations of the blade 29 will provide the necessary movement of the blade so that it will cut the hairs as the blade is moved over the skin surface.

Where lather or cream is used on the skin, the head of the device, which comprises the holder 20, may be placed in water or under a stream of water to clean the same, and due to the fact that there are no moving parts in the device, aside from the pulsating blade, the immersing of the head of the razor in water or under a stream of water will not short circuit any of the parts of the razor. The coil 11 is preferably encased in a waterproof casing, and if desired, the handle 15 may be made in two parts so that if the coil should become burned out the coil can be replaced.

I do not mean to confine myself to the exact details of construction herein disclosed, but claim all variations falling within the purview of the appended claims.

What I claim is:

1. An electric razor comprising an electro-magnetic operator adapted to be connected to an alternating current supply source, said operator comprising a coil and a U-shaped core having confronting extensions, a combined resilient armature and cutting blade suspendingly supported adjacent to said core extensions and within the electro-magnetic field of said core and adapted to vibrate at right angles to the longitudinal axis of said blade whereby the electro-magnetic pulsations of said core will be directly communicated to said combined armature and cutting blade causing said combined armature and cutting blade to vibrate at right angles to its longitudinal axis.
2. An electric razor comprising an electro-magnetic operator adapted to be connected to an alternating current supply source, said operator comprising a coil and a U-shaped core having confronting extensions, a combined resilient armature and cutting blade, means suspendingly supporting said combined armature and blade transversely of, and in close proximity to, said core extensions and within the electro-magnetic field of said core, and adapted to allow resilient movement of said armature and blade only at right angles to the longitudinal axis of said blade whereby the electro-magnetic pulsations of said core will be communicated directly to said combined armature and blade causing said blade to vibrate at right angles to the longitudinal axis of said blade.

EARLE E. DIETRICH.
